Ole O. Kolstad, INVENTOR
BY Victor J. Evans, ATTORNEY

UNITED STATES PATENT OFFICE.

OLE O. KOLSTAD, OF DULUTH, MINNESOTA.

MAIL BOX.

Application filed September 29, 1922. Serial No. 591,386.

To all whom it may concern:

Be it known that I, OLE O. KOLSTAD, a citizen of the United States, residing at Duluth, in the county of St. Louis and State of Minnesota, have invented new and useful Improvements in Mail Boxes, of which the following is a specification.

This invention relates to improvements in mail boxes, the general object of the invention being to provide a box for use in the rural districts and which is so formed that it will prevent damage of the mail by rain or snow and it will also prevent theft and the like.

Another object of the invention is to provide signal means on the box for indicating when the box contains mail.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view of the box showing the same in use.

Figure 2 is a longitudinal sectional view through the box.

Figure 3 is a rear view.

Figure 4 is a front view.

Figures 5 and 6 are detail views.

As shown in these views the body portion of the box 1 has an extension 2 laterally disposed at its upper part. The bottom of the extension extends at right angles to the adjacent side of the box, the top being curved, as at 3, said top extending over the extension. This curved top acts to shed water and snow. The front of the extension is left open, as at 4, and said opening is adapted to be covered by a hinged lid 5 which is flanged at its sides and bottom for overlapping the parts of the extension and the upper edge of the lid is provided with a flap 6 for making a water tight closure with the curved top. A curved plate 7 is provided for preventing a person taking mail from the box, said plate being pivoted at 8 with its curved portion overhanging the bottom, thereby mail and the like that is not heavy

enough to tilt this plate will be slidably deposited in the box. A substantially V-shaped spring 9 is secured to the box and projects under the extension 2 as shown. This spring is adapted for receiving outgoing mail. An opening 10 is formed in the lower rear side of the box, said opening being closed by a door 11 which may be locked by a padlock engaging opening in the angle part 12 which is arranged to pass through the slot 13 in the door. A flap 14 is provided for covering the hinged joint to prevent the entrance of water. The opening 10 has its lower edge slightly above the bottom of the box to leave a flange 15 for preventing the mail from dropping out when the door is opened. A substantially U-shaped reinforcing strip 16 is fastened upon the inner face and side walls of the box adjacent the lower end and a screw 17 passes therethrough for engaging a post 18 or the like, the upper end of which is spaced from the bottom of the extension to allow an appropriate space for operation of the out-going mail spring 9. A signal arm 18' is pivoted to one side of the box, as at 19, said arm having a weighted extension 20 which extends at an angle from the arm and acts to hold the arm in either its raised or lowered position, as shown in full and dotted lines in the drawings. When this arm is in raised position it will indicate that mail is in the box. A stop 21 is provided for limiting the movement of the arm.

As will be seen from the above the mail carrier can easily deposit mail in the box or take the mail therefrom and after the mail is deposited in the box the plate 7 will prevent any unauthorized person taking the mail therefrom. The box is entirely weather proof so that there is no danger of the mail being injured by the elements, and the peculiar construction of it permits the box to be placed on a post or the like so that the mail can be easily deposited therein and removed therefrom.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A mail box of the character described.

having a laterally disposed extension formed at its upper end and the rear wall of the box being curved over said extension to form the top thereof, a flanged closure for the extension and being hingedly secured to the curved top, a substantially U-shaped reinforcing strip secured to the inner face and side walls of the box adjacent its bottom, a fastening element passing through the reinforcing portion intermediate its ends and securing the box to a post so as to position the said extension in spaced relation from the top of the post and a substantially V-shaped spring having its ends secured to the box between the extension and post respectively for the purpose specified.

2. A mail box having an opening in its rear wall at its bottom, a hinged slotted closure for the opening, a flap depending over the hinged end of the closure, an open extension formed on the upper end of the

box, a flanged hinged closure for the extension, a flap extending inwardly from the upper end of the flanged closure and an apertured angle shaped projection secured to the bottom of the box and passing through the slotted closure for the purpose specified.

3. A mail box of the character described comprising a body portion, a lateral extension formed at the upper end of the body portion and the rear wall of the body portion being curved to provide the top wall for the extension, and a curved plate pivotally secured intermediate its ends at the juncture of the body portion and extension respectively with its curved portion overhanging the bottom of the box whereby mail that is heavy enough to tilt the plate will be slidably deposited therein.

In testimony whereof I affix my signature,

OLE O. KOLSTAD.
